UNITED STATES PATENT OFFICE.

FRANK H. HEITGER, OF INDIANAPOLIS, INDIANA.

CARBURETER.

1,090,208.

Specification of Letters Patent. Patented Mar. 17, 1914.

Application filed June 8, 1912. Serial No. 702,614.

To all whom it may concern:

Be it known that I, FRANK H. HEITGER, a citizen of the United States, residing at Indianapolis, Marion county, and State of Indiana, have invented and discovered certain new and useful Improvements in Carbureters, of which the following is a specification.

My said invention consists in certain improvements in the details of construction and arrangement of parts of carbureters and it especially relates to the mechanism for controlling the feed of the gasoline, or other hydro-carbon fluid, whereby the supply may be automatically regulated to suit the speed of the engine and conditions under which it is operating, all of which will be herein-after more fully described and claimed.

Referring to the accompanying drawings, which are made a part hereof and on which similar reference characters indicate similar parts, Figure 1 represents a side elevation of a carbureter embodying my said invention, Fig. 2 a central vertical section through the same; Fig. 3 a detail showing portions of Fig. 2 on an enlarged scale; Fig. 4 a cross section on the dotted line 4—4 in Fig. 3; Fig. 5 a cross section on the dotted line 5—5 in Fig. 3, and Fig. 6 a detail view showing a modification in the structure.

In said drawings portions marked A represent the mixing chamber, B the gasoline reservoir or float chamber, C an annular ring or easing section interposed between the top of said float chamber and said mixing chamber, and D the main air supply pipe. In the main these several parts as shown are of substantially a common construction, such as used on the well-known Heitger carbureter, and require no special description, except incidentally in describing the other parts to which my invention particularly relates.

The main features of construction, so far as novelty is concerned, are shown and described in detail in my companion application No. 702,616. The auxiliary air inlet valve 40 is mounted on a spring 41 as particularly shown and described in my companion application No. 702,612.

The mixing chamber has a suction tube 10 depending therefrom on the lower end of which is mounted a casting 11 containing the inlets for the gasoline and for the air. The spray nozzle 12 is screwed into the top

of the aperture in said casting 11 and is formed hollow and with a tapered seat 14 for the needle valve as most clearly indicated in Fig. 3.

The needle valve 15 comprises a hollow stem having a conical lower end adapted to fit within seat 14 and having longitudinal grooves spaced around its periphery near its lower end forming channels 16 through 60 which the supply of gasoline may be drawn into the carbureting chamber. The lower end of the perforation which extends centrally through the stem 15 is of small diameter and the upper end of a larger diameter, a shoulder 17 being formed between the large and small portions of the bore. As shown the extreme lower end is provided with a tip 25, with a small central perforation therein, driven into the lower end 65 of the tubular stem 15, which may be made of stock tubing for purposes of economy in construction. A reciprocating cylindrical valve 18 with a conical lower end is mounted in the large portion of the bore with its 70 point adapted to extend within and seat in the top end of the small portion at shoulder 17. An adjustable screw 19 is mounted in the upper end of said bore formed with a head 20 having a ribbed periphery adapted 75 to engage with a holding spring-detent 21 mounted on an adjacent part of the casing. The upper end of stem 15 is also provided with a head 22 having a ribbed periphery which engages with a spring-detent 23 on 80 an adjacent part of the casing. Said stem is screw-threaded for a distance just under said head and is mounted in a screw threaded perforation in the casing A, as shown, thus providing for the adjustment thereof 85 to fix the normal gasoline feed opening through the spray nozzle. Radial perforations 24 are formed through the wall of said stem leading into the portion of the bore containing the sliding valve 18 for permitting the gasoline to pass to the mixing chamber when valve 18 is raised from its seat on shoulder 17.

In operation the needle valve is adjusted by means of the head 22 to admit the normal 90 quantity of fluid fuel desired through the grooves 16 in the periphery of the lower end of said stem 15 and through the spray nozzle. Said supply will be fixed and regulated to the supply needed for low speed. 95 On the increase of the speed and the increase of the suction caused thereby, the

pressure or suction will be sufficient to cause valve 18 to rise in the enlarged upper end of the bore in stem 15 free from its seat on shoulder 17 and permit an additional supply of gasoline to flow through the central perforation in said stem and out through said radial perforations 24 into the mixing chamber. As the speed of the engine decreases, the weight of said valve 18 will cause it to fall and seat upon shoulder 17 and cut off this additional supply of gasoline. By means of the adjustment of screw 19 the vertical movement of said valve 18 may be limited so as to form a larger or smaller passage through the aperture at shoulder 17 when said valve is lifted to the limit of its movement. By this means the supply of fuel at the highest speed may be regulated and accurately limited as desired.

In Fig. 6 the means for regulating the supplemental supply of gasoline through the hollow stem is omitted and the parts shown to be fixed in a standard adjustment, any regulating desired being by means of the needle valve itself through the spray nozzle.

What I claim is—

1. In a carbureter, carbureting and mixing chambers, a fuel regulating mechanism comprising a hollow needle valve controlling the aperture leading from the fuel supply to the carbureting chamber, means for adjusting said needle valve to regulate the normal supply of fuel which may flow around the same, and an internal valve mounted within said hollow needle valve for controlling the flow through said needle valve to the mixing chamber, substantially as set forth.
2. In a carbureter, carbureting and mixing chambers, means for regulating the supply of gasoline to the carbureting chamber comprising a needle valve consisting of a

hollow stem with a valve on its lower end, means for adjusting said valve to regulate the supply flowing outside of said valve, 45 openings from the interior of said stem to the mixing chamber, a sliding valve within said hollow stem arranged to control the flow through said openings, and means for limiting the movement of said valve, substantially as set forth.

3. A carbureter comprising carbureting and mixing chambers, means for regulating the supply of gasoline consisting of a needle valve carried on a stem, said stem 55 formed with a longitudinal bore of different diameters with a shoulder between them, a valve mounted in the section of the bore having the larger diameter adapted to seat in the end of the section having the 60 smaller diameter, openings leading from said larger bore into the mixing chamber, a valve for controlling the flow through said bore, and means regulating said valve, substantially as set forth.

4. A carbureter comprising carbureting and mixing chambers, means for controlling the feed of the gasoline to the carbureting chamber consisting of a needle valve adapted to control the spray nozzle said needle 70 valve being formed with a longitudinal bore, apertures leading from said bore to the mixing chamber, and a valve for controlling the flow through said bore, substantially as set forth.

In witness whereof, I have hereunto set my hand and seal at Indianapolis, Indiana, this 21st day of May, A. D. nineteen hundred and twelve.

FRANK H. HEITGER. [L. S.]
